COMBINED FISH LURE AND WEED GUARD

Joseph J. Sabol, Hazleton, Pa., assignor of fifty percent to Joseph J. Ustynoski, Hazleton, Pa.

Filed Jan. 26, 1967, Ser. No. 5,570

Term of patent 14 years

(Cl. D22—27)

I claim:

The ornamental design for a combined fish lure and weed guard, substantially as shown.
